Attorneys

UNITED STATES PATENT OFFICE.

CHARLES K. ERNST, OF BUFFALO, NEW YORK.

AREA-WAY HOIST.

Application filed March 25, 1926. Serial No. 97,247.

This invention relates to that class of hoists which are employed for lifting ash barrels and other kinds of materials through an areaway from the basement or cellar 5 of a building to the sidewalk or street on the exterior of the same.

It is the object of this invention to provide an operating mechanism for a hoist of this character which is simple in construction, efficient in operation and capable of being easily manipulated for either raising or lowering the load without liability of getting out of order.

In the accompanying drawings:—
15 Figure 1, is a side elevation of my improved hoist showing the same arranged within an areaway.

Figure 2, is a rear elevation of the same partly in section.

20 Figure 3, is a vertical longitudinal section thereof.

Figure 4, is a horizontal section, taken on line 4—4, Fig. 2, on an enlarged scale.

Figure 5, is a fragmentary vertical section 25 on an enlarged scale taken on line 5—5, Fig. 2, and showing the means of locking the upper section with the mast in its elevated position on the lower section thereof.

Similar characters of reference indicate 30 like parts throughout the several views of the drawings.

The numeral 10 represents an areaway similar to those usually placed adjacent to the outer sides of buildings for the purpose 35 of providing a passageway through which ash barrels, freight and the like may be lifted from the cellar or basement of the building to the sidewalk or street. This areaway is usually closed at the top when 40 not in use by means of a movable cover or door 11 which may be mounted in any suitable manner.

Within this areaway and on one side 45 thereof is arranged the hoist which embodies my invention. This hoist in its general organization comprises a lower mast section 12 which is stationary, and an upper mast section 13 which is movable vertically on the lower mast section, means for raising 50 and lowering the upper mast section relative to the lower mast section and a drum and operating mechanism therefor mounted on the upper end of the upper mast section.

In the preferred construction the lower mast section comprises a channel iron 14 which 55 has its flanges 15 projecting forwardly and provided on the inner side of these flanges with angle irons 16 so as to form vertical guideways which open toward each other on the rear side of the channel iron 14. The 60 upper mast section is made up of two angle irons which are so arranged that two of their flanges 18 are parallel and project forwardly while their rear flanges 19 are in line and project laterally into engagement 65 with the guideways 17 of the lower mast section. The lower end of the lower mast section is preferably connected with a foot 20 which is in turn connected with the bottom or floor of the areaway, and the upper 70 end of the lower mast section is connected by a bracket 21 with the adjacent part of the wall of the areaway, as shown in Fig. 1. In this manner the upper mast section is guided in its vertical movements on the 75 lower mast section and reliably held in place during such movements.

Upon the upper end of the upper mast section are mounted the lifting means whereby the removal of the load from the cellar 80 through the areaway to the exterior of the building may be effected. These lifting means comprise a hoisting drum 22 upon the surface of which a hoisting line 23 is wound and unwound for the purpose of raising and 85 lowering the load which latter may be attached to this line in any suitable manner for instance by means of a hook 24. This drum is mounted on a shaft 25 which latter in turn is journaled on a supporting arm 90 26 which is mounted on the upper mast section. Rotation of the drum is effected by means of a crank shaft 27 journaled on the arm 26 and provided on one end thereof with a crank 28, and a pinion 29 arranged 95 on the opposite end of the crank shaft and meshing with a gear wheel 30 on the drum shaft.

For the purpose of permitting the drum supporting arm 26 to be either projected 100 from the upper mast section or swung back again to the mast in order to reduce the obstruction in the space in the areaway the supporting arm 26 is pivoted by means of an upright pin 31, and a supporting block 105 32 on the upper part of the upper section.

When in its projected position the drum arm may be held in place on the block 32 by means of a locking pin 33 on the drum arm and engaging with a recess 34 in the supporting block 32, as best shown in Fig. 3.

The means which embody my invention for raising and lowering the upper mast section and the parts mounted thereon are constructed as follows:

- 10 35 represents an upright gear rack which is arranged between the forwardly projecting flanges 18 of the upper mast section and secured thereto by means of rivets 36, as shown in Fig. 4, or by other suitable means. Arranged in rear of the upper part of the lower mast section is a driven shaft 37 which latter is journaled in suitable bearings 38 on the adjacent rear side of this mast section. Upon the central 15 part of this driven shaft is secured a gear pinion 39 which projects forwardly through an opening in the web of the channel iron 14 and into mesh with the teeth of the gear rack 35 so upon turning this gear pinion in 20 one direction or the other the upper mast section will be raised or lowered. This turning movement of the pinion 39 is derived from motion supplied manually by the attendant while occupying the lower part of 25 the areaway and for this purpose operating means are provided which extend from the shaft 37 downwardly to a point within reach of the attendant. These operating means in 30 their preferred construction comprise a longitudinal horizontal driving shaft 40 journaled in a bracket 41 on the lower part of the lower mast section, a hand crank 42 secured to one end of the driving shaft 40, an upright intermediate shaft 43 arranged 35 adjacent to the lower mast section and journaled at its lower end in a bearing on the bracket 41 while its upper end is journaled in a bearing on an upper bracket 44 secured 40 to the lower mast section, a pair of intermeshing gear wheels 45, 46 secured to the opposing lower ends of the driving shaft 40 and the upright shaft 43, and a pair of intermeshing gear wheels 47, 48 secured to the opposing ends of the intermediate shaft 43 and the driven shaft 37. Upon turning 45 the crank 42 in one direction or the other the gear pinion 39 will cause the gear rack 35 and the lifting drum mounted thereon to be raised or lowered. When the upper mast section is in its lowermost position the upper end thereof is below the areaway cover 11 and its lower end rests upon a stop 49 secured to the lower mast section. When the upper mast section reaches its normal elevated position the same is automatically 50 locked against downward motion by means of a catch which may be manually released. This catch preferably forms the arm 50 of the catch lever and is adapted to project 55 through an opening 51 in the web of the

channel iron into locking engagement with an opening 52 into one of the rear flanges 19 of the upper mast section. This catch lever is pivoted by means of a pin 53 to a bracket 54 on the rear side of the lower mast section and the same is yieldingly held by means of a spring 55 with its gage arm 51 in engagement with the opening 52, this spring being interposed between the rear side of the lower mast section and the lower operating arm 9 of the catch lever. In order to permit the attendant to operate this catch lever from the bottom of the areaway the operating arm 52 of this lever is provided with a rod 56 extending downwardly therefrom to a point within convenient reach of the attendant.

Upon raising the upper mast section the catch arm slides on the rear side of the upper mast section into the opening 52 and the upper mast section is presented to the catch and when this occurs the catch automatically enters the opening 52 and locks the upper mast section. Preparatory to lowering the upper mast section the attendant withdraws the catch arm 50 from the opening 52 and holds it out until the upper mast section has been lowered sufficiently to bring the opening 52 thereof out of register with the catch arm 50 after which the attendant may let go of the catch lever inasmuch as there is no further liability of the same re-engaging with the opening 52 but instead leaves the upper mast section free and to be lowered without further hindrance.

This hoisting mechanism for areaways is not only very simple in construction but the same can also be produced at low cost. Furthermore it is compact in construction, not liable to get out of order and permits of raising and lowering the lifting mechanism of the hoist with ease and facility.

In practice the mast is arranged sufficiently close to a wall of the areaway so that the supporting arm 26, when unlocked by the pin 33 from the supporting block 32, can be swung over the side walk, thereby permitting the load after it has been lifted to be deposited on the side walk and then disposed of in any suitable manner.

I claim as my invention:

An areaway hoist comprising a mast having a lower fixed section, and an upper movable section slidable vertically on said lower section, a hoisting drum mounted on said upper mast section, and operating means for raising and lowering said upper mast section on said lower mast section, comprising a vertical gear rack mounted on said upper mast section, a gear pinion meshing with said gear rack, a horizontal driven shaft journaled on the upper part of said lower mast section and carrying said gear pinion, a horizontal driving shaft journaled on the lower part of said lower mast section

and having a crank, an upright intermediate shaft journaled on the lower mast section, an upper pair of intermeshing bevel gear wheels connecting the upper end of said intermediate shaft with said upper horizontal shaft, and a lower pair of intermeshing bevel gear wheels connecting the lower end of

said intermediate shaft with said lower horizontal shaft, said upper horizontal shaft being arranged in rear of said lowermost section and at right angles to said lower horizontal shaft. 10

In testimony whereof I affix my signature.

CHARLES K. ERNST. .
